United States Patent Office.

WILLIAM M. HENDERSON, OF PHILADELPHIA, PENNSYLVANIA.

Letters Patent No. 65,911, dated June 18, 1867.

IMPROVEMENT IN STEAM-PUMP.

The Schedule referred to in these Letters Patent and making part of the same.

TO ALL WHOM IT MAY CONCERN:

Be it known that I, WILLIAM M. HENDERSON, of the city of Philadelphia, and State of Pennsylvania, have invented a new and useful Improvement in the Mode of Constructing Steam-Plunger Pumps; and I do hereby declare the following to be a full, clear, and exact description of the same, reference being had to the accompanying drawing, making a part of this specification, and to the letters of reference marked thereon, in which—

Figure 1 is a sectional elevation showing the general arrangement.

Figure 2, a front view of the same.

Figure 3, a detail of the valve-stem; and

Figure 4 shows the manner of forming the eccentric pin on the end of shaft.

The object of this invention is a plunger-pump, actuated by steam or other elastic fluid, with a view to strength, compactness, and simplicity of details, adapted to mines, steam vessels, rolling-mills, and other rough usage, where a failure to perform by a derangement of complicated parts would be dangerous, and consists in the construction of a single-acting plunger-pump, enveloped in a water-box, which answers the treble purpose of a vacuum-chamber, pocket for receiving the deposit of extraneous matter drawn in with the injection water, and also affords a stable base for the small barrel of the pump; the steam-cylinder being rigidly connected to it by a stout housing. Also in the direct manner of operating the valve, hereafter more fully described.

A is an inverted steam-cylinder; B the steam-piston, the rod C of which is made stout and long enough to answer as the ram of the pump D placed beneath, and far enough apart to allow of the cross-head arm E making the determined stroke; rotary motion being imparted thereto by a connecting-rod, F, to a crank-plate, G, whose shaft revolves in a bearing, H, cast on the cylinder head. The slide-valve I, is operated by means of a slot-headed valve-stem, J, as shown on fig. 3, directly from an eccentric pin, K, turned on the end, and in one piece with the shaft, which is made large so that the pin will be contained within the area of its cross-section, as shown by fig. 4. The pump is of the variety known as the common plunger-pump; the barrel being surrounded by an external casing; the space between the two forming a vacuum-chamber. This is also a pocket for receiving any deposit contained in the water, which can be discharged, as it accumulates, by a plug at the bottom of said chamber. Another advantage of this external casing is that it forms an expanded case for the diminutive barrel of the pump. The steam-cylinder is rigidly connected to this casing by standards L L; the whole forming a stout framework on a broad base-plate, M, which may be bolted to a foundation in the usual manner of securing steam engines. The induction and delivery-valves are contained in separate boxes outside, and are attached respectively to the vacuum-chamber at N N'.

What I claim as my invention, and desire to secure by Letters Patent, is—

The arrangement of the pump, steam-cylinder, and housing, as described.

The arrangement of a vacuum-chamber, enveloping the pump barrel, substantially in the manner and for the purposes represented.

The arrangement of the cross-head arm E, connecting-rod F, eccentric pin-shaft K, and slot-headed valve-stem J, when constructed and operating conjointly in the manner and for the purposes herein set forth.

WILLIAM M. HENDERSON.
